UNITED STATES PATENT OFFICE.

CARRIE M. DRAKE, OF FORT DODGE, IOWA.

SKIRT EVENER, TUCKER, HEMMER, AND MARKER.

1,344,871.

Specification of Letters Patent. Patented June 29, 1920.

Application filed May 21, 1919. Serial No. 298,686.

To all whom it may concern:

Be it known that I, CARRIE M. DRAKE, a citizen of the United States, residing at Fort Dodge, in the county of Webster, and State 5 of Iowa, have invented certain new and useful Improvements in Skirt Eveners, Tuckers, Hemmers, and Markers, of which the following is a specification.

This invention relates to measuring instruments, and more especially to tailors' 10 measures for use particularly on ladies' skirts; and the object of the same is to produce an instrument whereby the hem can be indicated at the desired distance from the ground and the tucks from the hem and 15 from each other at any desired distances, after which the skirt can be removed from the wearer or from the dress form and stitched.

20 The invention consists in a structure of substantially tripod shape whose front legs have series of openings at regular measured distances from each other and whose rear leg supports the front legs when the device 25 is set up, and rods are strung through certain of said openings at selective distances as will appear below. Means are also present for preventing undue spreading of the 30 feet of the tripod, while yet permitting the several elements to be assembled for storage 35 of the device. The structure may be used in the manner described below, and in the drawings,—

Figure 1 is an elevation of this invention 35 set up and in use.

Fig. 2 is a front elevation of the device alone.

Fig. 3 is an edge view of the same in its folded condition.

40 Fig. 4 is a perspective view.

While I refer hereinafter to the structure as of tripod shape, I do so merely because I have shown in the drawings two front elements or legs and a single rear element or 45 brace for the legs. Individually they are preferably of wood of appropriate dimensions, and the legs 1 and 2 shown herein are connected with the brace 3 at the upper end of all elements by a loose pivot 4 held in position in any suitable way. For preventing 50 undue spreading of the elements a restrainer is employed such as a chain 5 attached at its extremities at 6 to the legs and passing between its extremities around the brace as 55 shown. There should be at least three of

these elements and all should be united at their upper ends on a common pivot.

The legs 1 and 2 are formed with an upright series of perforations, preferably disposed in two rows and in staggered relation, 60 that row 8 near the front edge of each leg starting with its lower perforation preferably at one inch from the lower end of the leg and continuing upward in intervals of one inch, whereas the lower perforation of 65 the rear row 9 stands preferably at one and one-half inches from the lower end of the leg, while the other perforations in this row are spaced at inch intervals so that they stand opposite the points midway between 70 the perforations in the front row. Gage rods 10 are now provided as indicated in Figs. 2 and 4, and these are of a size to be passed through certain perforations and of a length somewhat greater than the distance 75 between the legs when the tripod is set up.

When stored away or in transit, the article is folded as seen in Fig. 3. When set up it appears as in Figs. 2 and 4, and when in use the whole appears as in Fig. 1. Let 80 us assume that it is desired that the hem of a skirt shall stand three inches above the floor and that there shall be two tucks above said hem, each two inches wide. Rods are passed through the perforations 8 in the 85 legs 1 and 2 as seen in Fig. 4. The skirt is now applied to the wearer or to a suitable dress form so as to cause the skirt to hang to one side of the tripod and behind the rods as indicated in Fig. 1, the rods being there- 90 in shown as of considerable length so that they extend quite across the skirt. The latter is initially of possibly sufficient length to reach the floor. The workman now pins up the goods to form tucks alining with or 95 possibly inclosing the uppermost two rods, and also pins up the lower edge of the goods to form the hem at the bottom of the skirt alining with or possibly inclosing the lower- 100 most rod. If the rods are inclosed as just suggested, the wearer turns around step by step to slip the hem or tucks off the ends of the rods as the work progresses, and this is continued all around the skirt with the re- 105 sult that the tucks are evenly spaced and the skirt is made of equal length throughout. Or, if it be desired to mark a skirt as for the subsequent formation of tucks or appli- 110 cation of braid, ruffles, etc., it is quite ob- 115 vious that a rod or rods may be passed

through the proper perforations, the wearer positioned close to them as shown in Fig. 1, and the skirt marked by the workman as she turns slowly around, the marking being done 5 by chalk, by the insertion of pins, or by making any suitable mark or indication on the skirt directly in alinement with the rod or rods in use. It will, of course, be understood that when the skirt is placed on a 10 dress form instead of on the wearer, said dress form will be turned or rotated step by step to permit the hems or tucks to be slipped off the ends of the rods.

Having thus described the invention, what 15 is claimed as new is:

1. A skirt measure comprising elements converging upward to a point of union and pierced with rows of perforations equally spaced from the lower ends of the elements 20 and from each other, and gage rods adapted to be passed through alined perforations.

2. A skirt measure comprising a tripod consisting of two legs at the front and a brace at the rear, all of said elements converging upward and being united pivotally, 25 restraining means for limiting the degree to which said elements may be spread, each leg having a row of transverse perforations spaced at measured intervals and a second row of perforations staggered with relation to said first row and gage rods selectively passed through alined perforations in the 30 legs.

3. A skirt measure comprising two legs 35 and a brace converging upward, a loose pivot connecting their upper ends, and a

flexible element connected with the legs and leading around the brace for limiting the degree to which these elements may be spread, said legs having like rows of transverse 40 perforations spaced at measured intervals from their lower ends upward, and gage rods adapted to be selectively passed through certain perforations.

4. A tripod comprising three elements 45 converging upward, a pin pivotally connecting them, and restraining means for limiting the degree to which the elements may be spread, combined with indicators adjustable on the legs at selected distances from their 50 lower ends and from each other.

5. In skirt measures the combination with a pair of legs having like rows of perforations spaced at measured intervals, and rods for insertion through alined perforations 55 for indicating a given distance of the skirt hem above the floor and given intervals between the tucks on the skirt; of an element connecting the upper ends of the legs, and means attached to said legs for supporting 60 the legs while in use.

6. A skirt measure comprising coacting legs having like rows of perforations spaced at measured intervals, rods for insertion through alined perforations for indicating 65 a given distance of the skirt hem above the floor and given intervals between the tucks on the skirt, and means for supporting the legs while in use.

In testimony whereof I affix my signature. 70

CARRIE M. DRAKE. [L.S.]
